United States Patent Office

Des. 223,688

Patented May 23, 1972

223,688

PEN CASING

Martin Schnur, Fort Lee, and Mel Appel, Livingston, N.J., assignors to Magic Marker Corporation, Glen-dale, N.Y.

Filed July 6, 1970, Ser. No. 23,829

Term of patent 14 years

Int. Cl. D19—06

U.S. Cl. D74—17

FIG. 1 is a top view of a pen casing showing our new design;

FIG. 2 is a side view thereof;

FIG. 3 is a bottom view thereof;

FIG. 4 is an end view thereof as seen from the right of FIG. 2; and

FIG. 5 is an end view as seen from the left of FIG. 2. We claim:

The ornamental design for a pen casing, as shown.
